(57) **CLAIM**

The ornamental design for a display screen of an electronic device with graphical user interface, as shown and described.

DESCRIPTION

FIG. 1 is a drawing showing a display screen of an electronic device with graphical user interface, in accordance with a first embodiment of the invention; and,

FIG. 2 is a drawing showing a display screen of an electronic device with graphical user interface, in accordance with a second embodiment of the invention.

The broken lines in the drawings illustrate portions of the display screen of an electronic device with graphical user interface that form no part of the claimed design.

1 Claim, 2 Drawing Sheets

FIG. 1

FIG. 2
